(57) **CLAIM**

The ornamental design for a clamp for laparoscopic device, as shown and described.

DESCRIPTION

FIG. 1 is a rear perspective view of a clamp for laparoscopic device, showing our new design;

FIG. 2 is a front perspective view thereof;

FIG. 3 is a left-side elevation view thereof;

FIG. 4 is a right-side elevation view thereof;

FIG. 5 is a bottom plan view thereof;

FIG. 6 is a top plan view thereof;

FIG. 7 is a rear elevation view thereof;

FIG. 8 is a front elevation view thereof; and,

FIG. 9 is a perspective view of the clamp for laparoscopic device shown in an environmental use.

The equally sized (dash-dash) broken lines showing a laparoscopic device in FIG. 9 depicts environmental subject matter that forms no part of the claimed design, while the alternating sized (dash-dot) broken lines shown in the drawings depict the bounds of the clamp for laparoscopic device that form no part of the claimed design.
